UNITED STATES PATENT OFFICE.

ERNEST C. ALLEN AND GEORGE F. PHILLIPS, OF ROCHESTER, NEW YORK, ASSIGNEES
TO EASTMAN KODAK COMPANY, OF ROCHESTER, NEW YORK, A CORPORATION OF
NEW YORK.

LOADING FIXTURE FOR FILM HOLDERS.

Application filed September 2, 1921. Serial No. 498,017.

To all whom it may concern:

Be it known that we, ERNEST C. ALLEN and GEORGE F. PHILLIPS, citizens of the United States of America, residing at Rochester, in the county of Monroe and State of New York, have invented certain new and useful Improvements in Loading Fixtures for Film Holders, of which the following is a full, clear, and exact specification.

10 This invention relates to photography and more particularly to loading fixtures for photographic film holders or hangers, and has for its object to provide a simple, compact and durable fixture for loading such 15 hangers rapidly. To these ends the improvements are directed particularly to the means for holding a hanger upright in a convenient position for loading; to means for using a variety of different sized hangers 20 in a single loading fixture; to means for properly guiding the film edges into the holder; and to means for guiding a hanger into the fixture in total or partial darkness. With these and other objects in view, the invention 25 consists of certain improvements and combinations of parts, all as will be hereinafter more fully described, the novel features being pointed out in the claims at the end of the specification.

30 While our fixture is adapted for use with a number of different types of film holders, it is particularly adapted for use with one of the type shown in U. S. Patent No. 1,363,184, N. E. Luboshez, granted Dec. 21, 35 1920; and such a film holder is shown, by way of illustration, in unshaded lines in the drawings. Hangers of the Luboshez type can be loaded without any fixture at all, but when a large quantity of work is to be 40 turned out in a minimum time, a loading fixture such as will be fully described in this specification saves much time and trouble, and increases the ease with which the film can be guided into position. This is particularly 45 useful with the larger sizes of film, as the film is liable to buckle and thus fail to enter the lower groove of the holder unless guided into place.

In the drawings, in which like reference 50 characters denote like parts throughout:

Fig. 1 is a perspective view of a loading fixture constructed in accordance with, and illustrating, one form of our invention with a film holder in loading position and a film 55 partially inserted;

Fig. 2 is a section across the loading fixture with a film holder partially moved towards the loading position;

Fig. 3 is a view similar to Fig. 2 but with the holder seated, and a film being guided 60 into position;

Fig. 4 is a fragmentary section through the line 4—4, but with the addition of a portion of a film holder between the rollers;

Fig. 5 is an end elevation of the fixture, 65 and

Fig. 6 is a modified form of film guiding roller.

As the film holder itself, designated generally by the letter H, forms no part of our 70 invention, it is shown in unshaded lines. The loading fixture consists of a flat base 1, which may have holes 2 (only one being shown in the drawing) through which screws may pass to hold the base in a convenient 75 location. Since it is most convenient to load a film holder by entering the film in the top and allowing it to drop by gravity into the holder, we provide means for positioning the holder in an erect position by means of upwardly extending arms 3—3 having slotted guideways 4—4 terminating on their upper ends in outwardly flared tops 5—5, to render the insertion of a film holder a simple 80 matter even in complete or partial darkness. These arms are preferably tilted slightly to one side of the vertical, so that a film F can be more conveniently slid into upper open ends O of the side channels of 85 holder H.

Film guiding rollers 6 and 7 are carried by shafts 8 and 9 which are supported in the slots 10 and 11 in the arms 3—3, the construction being the same in each case. These 90 slots permit the shafts to move from the innermost position, shown in Fig. 3, to the outermost position which is the limit set by the turn screws 13, there being one of these over the end of each of the four slots. A spring 13' passing about a turn screw 14 and 100 having the ends encircling shafts 8 and 9 tends to hold the rollers in their innermost position. One of these springs is carried by each arm 3.

If the loading fixture is to take only one 105 size of holder, the holder H will be supported on each side by the guide slots 4—4 in arms 3—3, and the rollers 6 and 7 may be of the same diameter throughout, such a roller being shown in Fig. 6, but as most 110

users desire a number of different size film holders, we support the smaller sizes by means of one guide slot 4 and reduced supporting surfaces 15—16 cut in the rollers 6 5 and 7, the diameter being such that they contact with the holder H when the rollers are in their innermost position, as shown in Fig. 4. In the present embodiment still additional supporting surfaces 17—18 are cut 10 in the rollers, so that this fixture will care for three different sizes of film holders. In Fig. 1 the intermediate size is shown in position for loading a film.

When the holder is in loading position, 15 the space 20 between rollers 6 and 7 is approximately that of the thickness of the film, and a portion of the periphery of the rollers forms a guide tapering to the center line of the shafts which guides the film accurately throughout its length into the bottom channel B of the holder H. The springs 13' permit the passage of channel B through the rollers 6 and 7 as the holder is slid into operative position with at least 25 one side in a guiding slot 4, as the rollers momentarily separate as channel B passes through to the base 1.

The operation of our loading fixture is as follows: The holder H (which we will assume is of the intermediate size as illustrated in Fig. 1) is thrust into loading position by entering one side into the outwardly flared top 5 of a guideway 4, and lowering the holder until the bottom passes through 35 the rollers to the base 1. The supporting surfaces 15—16 of rollers 6 and 7 contact with and hold the side of the holder which is not engaged by the guideway 4. The holder now stands at an angle to the base, in 40 a position in which the film F can be readily introduced into the side channels. The angle which the holder makes to the base is not material, the essential feature being that the end through which the film is inserted 45 shall be raised from the base a sufficient distance for convenient handling of the film. As the film slides down the channels, the rollers guide the lower edge into the channel at the bottom of holder H. A light pull 50 removes the holder from the fixture and it is ready for another holder.

Having thus described our invention, what we claim as new and desire to secure by Letters Patent is:

55 1. A loading fixture for film holders, comprising a base, and means on the base for supporting a film holder at an angle thereto.

60 2. A loading fixture for film holders, comprising a base, a guideway on the base, and resilient means for engaging a portion of a film holder as the holder is moved down

the guideway to support the holder in a loading position.

3. A loading fixture for film holders, comprising a base, means on the base for supporting a film holder in a loading position at an angle to the base, and means for guiding the film into the holder. 65

4. A loading fixture for film holders, comprising a base, arms extending upwardly 70 from the base, said arms having guideways adapted to position a film holder for loading, and means for guiding the film into the holder.

5. A loading fixture for film holders, comprising a base, arms extending upwardly 75 from the base and adapted to position a holder in loading position, and rollers carried by the arms adapted to guide the film into the holder. 80

6. A loading fixture for film holders, comprising a base, film guiding rollers, means for supporting the rollers including an arm supported by the base and having a guideway, said rollers being adapted to position 85 the film as it is slid into the holder.

7. A loading fixture for film holders, comprising a base, film guiding rollers, means for supporting the rollers including an arm supported by the base and having a guideway, and means carried by the rollers for engaging a portion of the film holder. 90

8. A loading fixture for film holders, comprising a base, arms extending upwardly 95 from the ends of the base and having holder guideways, film guide rollers resiliently supported upon the arms, being adapted to separate for the insertion of a holder into loading position.

9. A loading fixture for a film holder, 100 consisting of a base, a supporting member carried by the base and having a guideway for the holder, said guideway terminating in an outwardly flared portion adapted to direct the holder into the guideway. 105

10. A loading fixture for film holders, consisting of a base, a supporting member carried by the base for one side of a film holder, and spring actuated members for engaging the other side of the film holder 110 to position the holder for loading.

11. A loading fixture for film holders, consisting of a base, supporting arms carried by the base, guideways formed in the supporting arms, and guide rollers for directing 115 the film into a film holder, said rollers being provided with a plurality of film holder supporting surfaces.

Signed at Rochester, New York, this 30th day of August, 1921.
